UNITED STATES PATENT OFFICE

2,566,552

GLOVE SMOOTHING AND STRETCHING MACHINE

Teobaldo G. Boldizzoni, New York, N. Y.

Original application May 29, 1945, Serial No. 596,456, now Patent No. 2,511,455, dated June 13, 1950. Divided and this application June 9, 1945, Serial No. 598,582

6 Claims. (Cl. 223—79)

1

This invention relates to new and useful improvements in glove-smoothing and stretching devices, and especially to a device which, with a minimum of manual operations, accomplishes a perfect smoothing and also, if necessary, the ironing of a great number of gloves in little time and at small cost.

Hitherto the glove had to be smoothed manually by inserting into it two separate half forms and driving a wedge therebetween. These manual operations are not only strenuous and costly in time and labor but also the results are not sufficiently uniform; repetition is required. This makes manual stretching inaccurate, if not impractical, especially for inexpensive gloves.

It is an object of this invention to provide a device which is simple and easy to operate, even by inexperienced labor. The output is of uniformly high quality and costs less per unit than the result of the manual process.

A specific object of this invention is a glove-smoothing and stretching device containing a horizontal base; a glove form projects therefrom and consists of separable portions capable when brought together of receiving a glove thereon. Means are provided for mounting at least one of said portions on said base movable with respect to another so as to produce a predetermined space therebetween. By increasing this space the glove is stretched. By reducing this space, tension is relaxed and the glove form can be removed and placed in another glove which is treated in a similar manner.

According to the specific embodiment here disclosed, the form is divided into half portions, one or both of which may be moved. The portions are moved away from one another by being rotated about an axis at their bases. The space formed between the half portions extends preferably vertically upward. The movement of one or both of the half portions of the glove form is accomplished by a vertical upward movement of a wedge inserted in the space between the half portions. The wedge can be driven manually or electromechanically, or preferably by air pressure.

Further objects of this invention will be apparent from the accompanying drawings and the following description thereof which relate to an embodiment of the invention. In the drawings:

Fig. 1 is a side elevation, partly sectioned, of a glove-smoothing and stretching device embodying certain features of my invention;

Fig. 2 is a top view of Fig. 1;

Fig. 3 is an enlarged fragmentary view of Fig. 1 showing the anchorage of a glove form on a work-

2

ing table and a rod connection for actuating the wedge separating the half portions of the glove form;

Fig. 4 is a section along line 4—4 of Fig. 1, showing the mechanism above the working table and, in addition, the electric wire connections which are below the table and which serve to feed heater elements contained in the half portions of the glove form;

Fig. 5 is a section along line 5—5 of Fig. 1, showing the mechanism below the working table with the electrical connections omitted therefrom;

Fig. 6 is a view of a glove form partly broken away and recesses for the wedge and guide pins;

Fig. 7 is a section along line 7—7 of Fig. 6. This figure shows the wedge in operating position in which the thickness of the fingers of the glove form is increased; and

Fig. 8 is a section similar to Fig. 7 except that the wedge is inoperative position and the thickness of the fingers of the glove form is reduced.

In Fig. 1, 1 is a table upon which glove form 2 is mounted in an upright position. Glove form 2 consists of half portions 3 and 4 between which a space is formed extending vertically from table 1 with the distance between the half portions gradually diminishing. Half portion 3 is rigidly attached to table 1 by means of screws 5. Half portion 4 is hinged pivotally about horizontal axis 6. Axis 6 is supported on flange 7 which is rigidly attached to table 1 by means of screws 8. Half portion 4 is formed with a projection 9, the free end of which has attached thereto a compression spring 10 which seats in a recess of flange 7. In this way, half portion 4 can be moved with respect to stationary half portion 3. The movement is a rotation about axis 6 against the force of spring 10 to the position shown in dotted lines.

When a glove is mounted upon glove form 2, finger ironing and especially seam smoothing is accomplished by a pressing device which is more completely described in my copending application Serial No. 596,456, filed May 29, 1945, which matured into Patent No. 2,511,455, June 13, 1950 and of which application the present application is a division.

The pressing device consists of a number of parallel flexible metal strips 11, 12 and 13 made of spring steel, phosphor bronze or the like. Strips 11, 12 and 13 are parallel to one another so as to be insertable between the fingers of a glove mounted upon form 2. The strips are rotatable about horizontal axis 14 which is supported between brackets 15.

Brackets 15 are attached to table 1 by means of screws 16. Strips 11, 12 and 13 carry pressure elements in the form of flexibly mounted rollers 17; these rollers are arranged on each side of the strips in such a way as to smooth the seams of the glove when the strips are rotating about axis 14. The rotation is accomplished by means of a lever 18 which engages the free ends of strips 11, 12 and 13, or as shown in Figs. 1 and 2, the projecting end 19 of a holder 20 to which strips 11, 12 and 13 are attached. Holder 20 is a piece of casting with a slot 21 into which strip 12 is fitted while strips 11 and 13 can be attached to casting 20 by angle pieces 22. Screws 23 passing through casting 20, strips 11, 12 and 13, angle pieces 22 serve to connect strips and holder so as to form a relatively rigid unit. Springs 24 are attached at one end to the horizontal flanges of angle pieces 22. The other ends of springs 24 are attached to brackets 15 at points 25. In this way, the upward movement of strips 11, 12 and 13 is made flexible and is caused to occur against the force of expanding springs 24. Lever 18 is moved down or up by cross lever 26 which is pivotally hinged at 27 underneath table 1.

As explained in my Patent No. 2,511,455, by the movement of lever 26, lever 18 and strips 11, 12 and 13 are moved and finger-pressing and seam-smoothing operations are performed. The inoperative position of strips 11, 12 and 13 is shown in dash-dotted lines at 28; the inoperative positions of levers 18 and 26 are shown at 29 and 30, respectively.

In accordance with my invention the glove mounted upon form 2 is smoothed by a stretching operation. This is accomplished by driving a wedge in the space between half portions 3 and 4. The wedge is indicated in Fig. 1 at 31. Its operative movement occurs in vertical direction under the control of vertical rod 32 which engages the bottom end of the wedge through a flexible spring coupling 33. Vertical rod 32 is operated either manually or electromechanically, or as shown schematically in Fig. 1, by means of air pressure. A cylinder 34 is mounted in a manner not fully shown beneath table 1. At the lower end of rod 32 is piston 35 in cylinder 34. Air is admitted through conduit 36 selectively on either side of the piston. This causes the desired upward or downward movement of rod 32. The air admission is regulated mechanically or electromechanically by valves contained in box 37 through buttons 38 arranged on top of table 1. After having opened inlet valve 39, the operator presses buttons 38 which actuate the air valves and move rod 32 upward or downward. Strips 11, 12 and 13 are moved out of or into operative position with respect to a glove mounted on form 2 as explained in my co-pending application. Simultaneously, rod 32 acts on spring 33 and moves wedge 31 upward or downward, into or out of operative position. Thus, the glove is stretched or released and ready to be removed.

The anchorage of glove form 2 on table 1 and the connection of rod 32 for actuating wedge 31 of the form 2 is shown in an enlarged scale in Fig. 3.

Half portion 3 is shown attached to table top 40 by means of screws 5. Half portion 4 is hinged on axis 6. The space between half portions 3 and 4 has a trapezoidal cross-section. The side wall form at half portion 4 is inclined with respect to the vertical so that the space between 3 and 4 gradually diminishes while extending upward. Wedge 31 has the shape shown in Fig. 7;

it consists of good heat-conducting metal, such as copper, aluminum casting or the like. A recess 41 in wedge 31 serves to receive coupling spring 33. A vertical slide slot 42 for the guide pins 43 and 44 helps to insure accurate alignment of wedge 31 during its upward movement in the space between portions 3 and 4.

Fig. 7 shows wedge 31 in operative position; in Fig. 8 wedge 31 is in inoperative position. In the latter position, because of the action of spring 10, half portion 4 approaches half portion 3 under the urge of spring 10 (Fig. 1); the glove tension is released and the glove can be removed from form 2.

As shown in Fig. 3 these stretching and releasing forces are transmitted to wedge 31 by rod 32 through coupling spring 33. Spring 33 is slipped over bolt 45 and presses at one end against the wall of recess 41. The head 46 of bolt 45 fits into recess 47 of rod 32 and is prevented from leaving this recess by means of a cap 48 which is screwed on rod 32 and covers recess 47. The other end of spring 33 presses against the top of cap 48. In this way, up and down movements of wedge 31 are made flexible.

As shown in Figs. 3, 6, 7 and 8, half portions 3 and 4 each contain an electric heater element 49. The heater wire is insulated by asbestos 60 or similar insulating material because the half portions 3 and 4 consist of good heat-conducting material which usually is also an electrical conductor.

As shown more clearly in Figs. 6, 7 and 8, the heater wire 49 is positioned in recess 50 formed in half portions 3 and 4, respectively. The heater wire 49, when leaving half portions 3 and 4 at 51 (Fig. 1) can be connected in parallel or in series, as the case may be, or conducted separately in the direction of arrow 52 to a switch as shown more clearly in Fig. 4. Wires 54 are passed on the underside of table 1 into conduit 53 and, from there, into switch box 54. Switch buttons 55 below table 1 serve to energize the heater elements. Naturally, if desired, switch buttons 58 above table 1 and buttons 55 below table 1 can be combined in a single unit.

While Fig. 4 shows the wiring above table 1, Fig. 5 shows the arrangement of the air control mechanism below the table 1.

In Fig. 5 the cross lever is again indicated at 26; it is mounted on axis 27 supported in bearings of angle pieces 56 which are attached to the underside of table 1. Air tubes 57 and 58 in conduit 36 serve for selective admission of air to either side of piston 35 (Fig. 1), thus operating the up and down movements of rod 32.

While I have shown and described the operation of the device with respect to one glove form, it will be obvious to those skilled in the art that modifications and variations to the device are possible without departing from the scope of the invention.

What I claim is:

1. In a glove-stretching device, a horizontal base, a glove form projecting therefrom and comprising two parallel separable half portions capable when brought together of receiving a glove thereon, means for mounting one of said half portions stationary on said table, means for mounting the other of said half portions rotatably on said table, a spring attached between the rotary half portion and the base for normally holding the half portions together, and a wedge movable between the half portions for separating them.

2. A device according to claim 1 wherein the stationary half portion consists of a vertical finger portion extending into a horizontal flange rigidly attached to the base and wherein the rotary half portion comprises a substantially vertical finger portion, a flange rigidly attached to the base and containing a pivot supporting said rotary finger portion rotatable about a horizontal axis arranged closely to the base, said rotary finger portion having a substantially horizontal extension disposed above and in spaced relation to said second flange, and a spring disposed between the extension and flange for normally urging the fingers toward each other while permitting separation of the fingers against the action of said spring.

3. In a glove smoothing device, a base, a glove form having separable portions projecting from said base, a wedge between said portions, means for mounting one of said portions movable with respect to another on said base, means for moving said wedge to separate said portions gradually, the last mentioned means including a plunger, a spring coupling between the plunger and the wedge, and means for moving said plunger, and at least one heater element in each of the separable portions.

4. In a glove-stretching device, a horizontal base, a glove form vertically projecting therefrom comprising two substantially parallel separable half portions capable when brought together of receiving a glove thereon, means for mounting one of said half portions stationary on said base, means for mounting the other of said half portions rotatably on said base having a horizontal axis of rotation close to the base, the space between the half portions normally having a trapezoidal cross-section, a wedge arranged to be inserted in said space, a vertical plunger for moving said wedge in a vertical direction into said space to separate said half portions gradually, a spring for the wedge having one end connected to the wedge and the other end to said plunger, and

means for driving said plunger in a vertical direction, said driving means including an air cylinder acting upon said plunger to move it in vertical direction.

5. In a glove-smoothing device, a base, a glove form having separable portions projecting from said base, a wedge between said portions, means for mounting one of said portions movable with respect to another on said base, means for longitudinally moving said wedge with respect to said form to produce a predetermined separation between said portions, said last mentioned means including a plunger, a spring coupling between the plunger and the wedge and means for moving said plunger.

6. In a glove stretching device, a horizontal base, a glove form projecting therefrom and comprising two separable half portions arranged to form a space therebetween when stretching a glove thereon, means for mounting one of said half portions stationary on said base, means for mounting the other of said half portions rotatably on said base, a wedge arranged to be inserted in said space to separate said half portions, a vertical plunger for moving said wedge in a vertical direction into said space to separate said half portions gradually, a spring intermediate the plunger and the wedge forming a flexible coupling therebetween, an air cylinder arranged beneath the base and connected to drive said plunger in a vertical direction when operated.
